DOUBLE EDGE INJECTOR RAZOR
George Treiss, 100 Westbrook Drive,
Lancaster, Pa. 17600
Filed Mar. 2, 1966, Ser. No. 531,169
3 Claims. (Cl. 30—63)

ABSTRACT OF THE DISCLOSURE

A double edge injector razor with provisions for varying the position of the head in which the blade is carried and for adjusting the cutting angle of the blade as desired, one edge of the blade being exposed for cutting and the other edge being protected until exposed for use.

This invention relates to an adjustable double edge injector razor and magazine. The present razors available on the market all have certain disadvantages. In many razors now available, in order to change blades it is necessary to change the blade edge exposure setting and to practically disassemble the entire razor. This requires an unnecessary waste of time, and trial and error adjustment to again obtain a satisfactory blade edge exposure. The presently available razors do not have protection for the blade edge when not in use. Injector razors now available facilitate the insertion and removal of the blade but these have only one cutting edge and lack or have limited adjustment of the blade edge.

The principal object of the present invention is to provide a double edge injector razor and magazine wherein the blade can be readily changed and adjusted as desired.

A further object of the present invention is to provide a double edge injector razor wherein only one edge at a time is exposed for shaving with the other edge protected until ready for use.

A further object of the present invention is to provide a double edge injector razor wherein both edges of the blade are protected when the blade head is in a neutral and out of use position.

A further object of the present invention is to provide a double edge injector razor and magazine wherein the blade head may be moved to alternate positions exposing either side of the blade, or to a neutral position for blade edge protection.

A further object of the present invention is to provide a double edge injector razor wherein the blade edge exposure may be varied and positively locked in a multiplicity of positions.

A further object of the present invention is to provide a double edge injector razor and magazine wherein the blade may be inserted from either side of the blade head in any position.

A further object of the present invention is to provide a double edge injector razor and magazine that is simple and inexpensive to manufacture but rugged and durable in operation.

A further object of the present invention is to provide a double edge injector razor and magazine wherein the blades are securely held in the magazine and positive ejection of one blade at a time is provided.

A further object of the present invention is to provide a double edge injector razor and magazine wherein the injection of the new blades into the razor head positively ejects the old blade and accurately and easily positions the blade in the razor head, both edges of the blade being protected during insertion.

A further object of the present invention is to provide a double edge injector razor wherein the blade is securely

2

held at its four corners but which can be easily and quickly replaced if desired.

A further object of the present invention is to provide a double edge injector razor wherein the magazine operates with the razor head to permit insertion of new blades therein.

Other objects and advantageous features of the invention will be apparent from the description and claims.

The nature and characteristic features of the invention will be more readily understood from the following description taken in connection with the accompanying drawings forming part thereof, in which:

FIGURE 1 is a view in perspective of a double edge injector razor in accordance with the invention and in one position for shaving;

FIG. 2 is a vertical sectional view taken approximately on the line 2—2 of FIG. 1;

FIG. 3 is a fragmentary vertical sectional view similar to FIG. 2 showing the razor head in central position;

FIG. 3A is a fragmentary sectional view taken approximately on the line 3A—3A of FIG. 2;

FIG. 4 is a vertical sectional fragmentary view taken approximately on the line 4—4 of FIG. 3;

FIG. 5 is a vertical sectional view taken approximately on the line 5—5 of FIG. 4;

FIG. 6 is a fragmentary vertical sectional view, enlarged, taken approximately on the line 6—6 of FIG. 2;

FIG. 7 is a view in perspective showing an internal hinged or pivotal support employed in connection with the invention;

FIG. 8 is a horizontal sectional view, enlarged, taken approximately on the line 8—8 of FIG. 2;

FIG. 9 is a horizontal sectional view, enlarged, taken approximately on the line 9—9 of FIG. 2;

FIG. 10 is a horizontal sectional view, enlarged, taken approximately on the line 10—10 of FIG. 2;

FIG. 11 is a view in perspective showing a double edge injector razor blade used in accordance with the present invention;

FIG. 12 is a view in perspective illustrating the magazine and injector razor in position for the insertion of a razor blade into the razor head of the present invention;

FIG. 13 is a vertical sectional view taken approximately on the line 13—13 of FIG. 12;

FIG. 14 is a horizontal sectional view taken approximately on the line 14—14 of FIG. 13; and

FIG. 15 is a vertical sectional view taken approximately on the line 15—15 of FIG. 13.

It should, of course, be understood that the description and drawings herein are illustrative merely, and that various modifications and changes can be made in the structure disclosed without departing from the spirit of the invention.

Like numerals refer to like parts throughout the several views.

Referring now more particularly to the drawings and specifically FIGS. 1 to 12 thereof, an adjustable double edge injector razor 10 in accordance with the invention is illustrated. The razor 10 includes a razor head 11 and handle 12. The handle 12 has an outer housing 14 composed of two like semi-cylindrical ribbed strip portions 15 and two like rectangular strips 16. The strips 15 can be of synthetic plastic material, such as nylon, but other suitable materials may be used. The strips 16 are preferably made of thin gauge spring type metal. The strips 15 have two lengthwise extending grooves 17 wherein the two metal strips 16 are retained. The plastic strips 15 are held together at 20 by corresponding symmetrical inwardly extending pins 21 and sockets 22 which are fitted together during assembly, one of the three pairs 20 being illustrated in more detail in FIG. 8.

The handle 12 at the lowermost portion thereof has a ribbed cylindrical knob 23 thereon carried on a vertical upwardly extending shaft 24. The knob 23 has detent holes 25 in the topmost surface 26 for engagement by dimples 27 in a spring 28 which is retained in the strips 15 and bears on the top surface 26 of the knob 23. The knob 23 can have as many holes 25 as desired and to provide the desired range of blade adjustment, eight being a preferred number. The knob 23 has number indicia engraved or otherwise marked on its outside surface corresponding to the detent holes 25. The upwardly extending shaft 24 is journaled at its lower end 31 in a plate 30 which is joined to the strips 15 and 16 at its outer edge and serves also to hold the strips 15 and 16 together. The shaft 24 is journaled at its upper end 32 in a plate 33 which is similar to plate 30 and is securely fastened to the strips 15 and 16 at its outer edge. Two retaining collars 34 are provided attached to the shaft 24 one on each side of the plate 33 which collars 34 serve to prevent vertical movement of the shaft 24.

The shaft 24 on the upper side of plate 33 terminates in a hollow interiorly threaded screw receiving socket portion 36. A shaft 37 is provided threadably engaged at its lower end in the threaded socket portion 36 of the shaft 24. The shaft 37 extends vertically upwardly through a hole 38 in a base plate 39 and through a collar 40 and is integral with a horizontal shaft 41 of razor blade base assembly 42. A helical spring 44 on the shaft 37 is interposed between the collar 40 and the base plate 39.

The base plate 39, as shown more fully in FIG. 7, is of rectangular shape carried in retaining brackets 43 in strips 15 with two vertical upwardly extending support arms 45 carried thereby and integral therewith. The arms 45 have two horizontally outwardly extending half cylindrical bearings 46 integral therewith having outer curved bearing surfaces 47 and inner curved bearing surfaces 48.

The razor blade head 11 has an outer housing 50 which is composed of two symmetrical halves 51. The halves 51 each has a downward plate 52 of curved shape in cross section, the plates 52 being retained and pressed together by the upper end portions of strips 16.

Referring now specifically to FIGS. 2, 3, 5 and 7 the housing plates 52 have on the bottom thereof downwardly extending arcuate arms 55 which extend around the outer surface 47 and retain the blade housing 50 to the bearings 46.

Two bearing ribs 56 are also provided on the plate portions 52 spaced interiorly of arms 55 and which engage the inner bearing surfaces 48 of the bearings 46.

The plates 52 have attaching plates 57 extending upwardly integral therewith which plates 57 have vertical ears 58 on each end thereof connected by a curved guard plate 60.

The attaching plates 57 at their lower portions have stop ledges 59 and 67 for resilient engagement by the upper end portions of the spring strips 16. A slot 61 is provided between guard plate 60 and plate 57 for the reception of a razor blade bed plate 62. The ears 58 of the housing 50 each has a key or tongue hole 54 therein for the reception of a tongue 70 of a blade magazine 71. The ears 58 each also has one half of a horizontal blade receiving slot 63 formed therein for the reception of a razor blade 75. The ears 58 at the ends of the slot 63 have blade engaging face portions 77 which engage the upper surface of the blade 75 at the corners thereof when the housing half sections 51 are held together and in their central and tilting operating positions, and engaged by the bed plates 62. The bed plates 62 have horizontal serrated guard bars or ribs 72 extending therealong and bearing on the outer edge 58a of ears 58 to provide a guard for the edge 100 of the razor blade 75 as shown more fully in FIG. 3A. The razor blade bed plates 62 are symmetrical and attached to angularly inclined downwardly extending legs 64 which legs 64 are re-

tained and held together at the bottom by a spring retaining clip 65. The clip 65 extends around the shaft 41 which is held by the legs 64, with a struck out portion 66 to permit the shaft 37 to pass therethrough and engage the shaft 41. The clip 65 has two tongues 68 which are centrally located and engaged in slots 69 in the legs 64, the bottom portion of the clip 65 bearing on top of collar 40 which is urged upwardly by spring 44.

The clip 65 draws the legs 64 together and accordingly bed plates 62, guard bars 72 as well as the head portion 11 are held in assembled relation.

The blade magazine 71, as illustrated in FIGS. 12 to 15, includes an outer housing 80 of synthetic plastic or other material as desired. The housing 80 has upper horizontal wall 81, lower horizontal wall 82, vertical front wall 90, inclined rear wall 91, and vertical side connecting walls 83. The upper wall 81 has a slot 84 therein extending its length for the reception of a tapered rectangular blade engaging tongue 85 of a blade pusher 86. The blade pusher 86 has an upper plate 87 attached to the tongue 85 and with suitable gripping surface 88 thereon. The housing 80, on the front wall 90 thereof, has a tongue 70 thereon of tapered rectangular shape adapted to engage the slot 54 in the ears 58 and is adapted to spread the ears 58 for insertion of a blade 75 into the razor 10. The wall 90 has a slot 92 therein at the top thereof of such height and width as to permit a single blade 75 to pass therethrough. A spring 94 is shown which bears on the bottom wall 82 and the lowermost blade of a stack of razor blades 75 urging a stack of blades 75 upwardly along guide ribs 96 and 97 for engagement by the tongue 85 of the pusher 86. The guide ribs 96 and 97 orient the blades 75 and position them for movement upwardly and for directed and guided discharge. Projections 98 are provided beneath the top wall 81 for engagement by projections 99 on the pusher 86 for limiting the outward movement of the pusher 86.

A preferred form of blade 75 (see FIG. 11) is of rectangular shape with two cutting edges 100 and tapered slots 101 in front and rear edges 102 and 103 of the blade 75. The slots 101 are adapted to receive the pusher tongue 85 and due to their taper do not hang up on the tongue 85. The interengagement of the pusher tongue 85 and slot 101 orients the blade 75 to be advanced and during advancing.

At the same time upon return of the tongue 85 with overtravel engagement clearance is provided to facilitate engagement at the slot 101 of the next blade to be advanced.

The mode of use will now be pointed out.

The razor 10 may have its blade head 11 moved to any desired position, as shown in FIGS. 2, 3 and 12. The tongue 70 of the blade magazine 71 is inserted into the hole 54. This tongue 70 causes the housing halves 51 to separate and any old blade upon insertion is no longer secured in the head 11. This separation also provides clearance for entry of the pusher tongue 85. The blade pusher 86 is moved forward in the slot 84 wherein the topmost blade of the blades 75 is engaged by the pusher tongue 85 in its slot 101. Further movement of the pusher 86 forces the blade 75 out the slot 92 and into the slot 63 in the blade head 11. This forward movement continues until the blade is positioned as desired or stop 98 is reached. Entry of a new blade 75 from the magazine 71 effects ejection of the old blade 75 through the opposite blade access opening 63.

The tongue 70 of magazine 71 is withdrawn from the hole 54 and the halves 51 of the housing 50 are forced back together by the spring strips 16 and the clip 65. The blade 75 is then gripped at its four corners by the inside edges 77 of the ears 58.

In order to obtain blade edge exposure for shaving, the razor head 11 is moved either to the right or left position to expose above one of the guide bars 72 one edge 100 of the blade 75 for use, while protecting the other edge

100 by its downward movement in slot 61 below the top edge of the guard bar 72. The tilting of the bed plates 62 with respect to the blade 75 and guard plate 60 effects such edge exposure, as shown in FIG. 2 from a protected blade position as shown in FIG. 3.

The knob 23 is then turned to the desired numbered position. The shaft 24 thru threads 36 and shaft 37, causes the blade base assembly 42 to move upward or downward depending on the blade edge exposure required and direction of motion of knob 23 which acts on the base plate 62 to cause greater or less of the blade edge 100 to be exposed above the guard bar 72 in the slot 61. Further adjustment can be made as desired. When the other blade edge 100 is desired to be utilized for shaving, the blade head 11 is moved to opposite position and used as needed without any further adjustment unless adjustment is desired.

It will be noted that the central positioning of the head 11, illustrated particularly in FIG. 3, provides for guarding the blade edges 100 during shipping, and between successive uses, for protection of the blade edges 100 and for safety.

I claim:

1. A double edge injector razor comprising
a blade having opposite longitudinal cutting edges, 25
a handle,
a blade receiving and holding head having opposite
separable housing portions,
each of said housing portions having ends with an outer
guard plate and a guard bar therebetween,
said housing portions each having a longitudinal slot
between the guard plate and the guard bar for blade
edge exposure,
said housing portion having aligned slots in said ends
for blade access,
said housing portion each having blade engaging por-
tions at the ends of the longitudinal slot for engage-
ment with top corners of the blade,

opposite bed plates at least one of which is in longitudinal central engagement with the blade, 5
pivotal connections between said housing portions and
said handle for shifting said head to a cutting position,

10
pivotal connections between said bed plates and said
handle, and
members carried by said handle for varying the relative locations of said pivotal connections and there-
by varying the cutting edge exposure of the blade.

15
2. A double edge injector razor as defined in claim 1
in which

said pivotal connections between said bed plates and
said handle has a shaft extending longitudinally of
said handle, and
a positioning shaft in threaded engagement with said
first mentioned shaft, and
a positioning knob connected to said positioning shaft
for rotating said positioning shaft.

20
3. A double edge injector razor as defined in claim 1
in which

said housing portions are separable,
said bed plates are separable and have leg portions,
a resilient clip holds said housing portions and said
leg portions in assembled relation.
